UNITED STATES PATENT OFFICE.

DANIEL WEBSTER TOWER, OF GRAND RAPIDS, MICHIGAN, ASSIGNOR TO GRAND RAPIDS BRASS CO., OF GRAND RAPIDS, MICHIGAN, A CORPORATION OF MICHIGAN.

LATCH CONSTRUCTION.

1,351,222.

Specification of Letters Patent. Patented Aug. 31, 1920.

Application filed December 4, 1918. Serial No. 265,249.

To all whom it may concern:

Be it known that I, DANIEL W. TOWER, a citizen of the United States of America, residing at Grand Rapids, in the county of Kent and State of Michigan, have invented certain new and useful Improvements in Latch Constructions; and I do hereby declare the following to be a full, clear, and exact description of the invention, such as will enable others skilled in the art to which it appertains to make and use the same.

This invention relates to latch constructions, particularly adapted for use on refrigerators, and it is the primary object and purpose of the invention to produce a latch construction which may be formed entirely from sheet metal at a relatively low cost of manufacture and which is adapted for use on refrigerators or like structures, serving to automatically hold the door closed as it is moved to closed position, yet readily operable to release the door for opening whenever desired. The invention comprises many novel structural features and arrangements of parts for successfully attaining these ends, as will fully appear in detail from the following description, taken in connection with the accompanying drawings showing a preferred embodiment of the invention, in which drawings,

Figure 1 is a front elevation showing the latch construction applied to a door and casing or jamb therefor, said door and jamb being disclosed in fragmentary portions only.

Fig. 2 is a side elevation thereof.

Fig. 3 is an under plan of the latch which is attached to the door.

Fig. 4 is a vertical section taken substantially on the line 4—4 of Fig. 3.

Fig. 5 is a side elevation of the adjustable keeper adapting the latch for attachment to different thicknesses of doors, the view being from the side opposite to that shown in Fig. 2.

Fig. 6 is a view looking at the bottom of the keeper.

Fig. 7 is a side elevation of one of the members going to make up the adjustable keeper.

Fig. 8 is a side elevation, partly broken

away and in section, of the operating handle for the latch, and

Fig. 9 is an under plan of the latch housing, the under covering plate for the lock mechanism of the latch being removed.

Like reference characters refer to like parts in the different views of the drawings.

The latch is secured adjacent the free vertical edge of a door 1, and the keeper associated therewith is attached to the door jamb or casing 2 in position to cooperate therewith. The latch, in construction, includes a housing 3, the interior portion of which is raised to form a housing for the lock mechanism for the latch, said housing being indicated at 4, while a portion 5 is raised still higher adjacent one side of the housing member 3 in which the actuating spring of the latch is housed. This housing member is secured to the door by means of screws or similar attaching devices and is brought either to the edge of the door as shown or very close thereto, there being a slight choice of position for the latch at the free edge of the door as will later appear. In the upper side of the housing portion 5 a slot 6 is cut and within said portion 5 and along its outer side a plate 7 is positioned, it having a reduced projection 8 passing through the upper side of the portion 5. The plate 7 is fixed to the housing by electric welding, the spots of welding being indicated at 7a.

The handle of the latch is pivotally connected to and depends from said projection 8. In construction the handle is formed from three pieces of sheet metal 9, 10 and 11, the pieces 9 and 10 being separated at their upper ends to pass one each side of the projection 8 and being bent together at their lower ends and inserted into the upper end of the part 11 which is formed into handle shape as shown. Parts 9, 10 and 11 are then securely connected by electric welds, this forming a rigid and strong connection. The pivot passes through said pieces 9 and 10 after which the upper portion of the piece 10 is passed inwardly through slot 6 forming an arm 12 between which and the lower end of the housing portion 5 a coiled spring 13 under compression is interposed,

its ends being held in place by a projection 12^a on the arm 12, and a tang 14 struck inwardly from the portion 5. The other piece 9 of the handle is likewise formed with an 5 inwardly extending arm 15 which passes along the outer side of the housing portion 5 for a distance and is then bent laterally, making a section 16 around which a sleeve 17 of metal is placed and secured by electric welding, the weld being indicated at 10 17^a in Fig. 3.

The keeper includes in its construction a base 18 and an outwardly projecting integral arm 19 formed from sheet metal, along- 15 side of which is positioned a plate 20, also of sheet metal, which, at its outer end has a downwardly and inwardly inclined edge 21, back of which is a substantially vertical edge 22, inclined slightly to the rear as shown. A slot 23 is cut in the member 20 and a screw 24 passes through the arm 19 and the slot 23, threading through one leg 25 of a reinforcing angle, the other leg 26 of which passes under the base 18 and is 20 secured thereto by electric welding as indicated at 26^a. With this construction, the plate 20 may be adjusted in or out with respect to the base 18 and the door jamb 2 to which it is attached by screws, as is evident, 25

30 A latch and keeper therefor of the construction described when attached, respectively, to the door and the door jamb of a refrigerator or like structure serve to hold the door in tightly closed position, it being evident that when the door is closed, sleeve 17 rides against and under the incline 21 until it passes back of the edge 22, whereupon the force of spring 13 tends to force the sleeve 17 upwardly against the slight rearward incline of said edge 22, holding the door in tightly closed position. This action takes place automatically with the closing of the door. To open the door it is merely necessary to grasp the handle 11 and impart an 40 outward pull to the same, whereupon spring 13 is compressed and the sleeve 17 moved so as to pass the lower projection of the keeper, the door opening with the one operation. With different doors having different rises 45 over the door jamb, it is merely necessary to adjust the keeper member 20 to proper position, and by reason of the fact that the sleeve 17 is positioned above the outer surface of the door, the latch may be removed 50 slightly away from the extreme edge of the door, if desired, the keeper necessarily moving closer to the edge of the jamb if this is done.

55 A locking mechanism may be added to the latch, occupying the space under the lower raised housing portion 4. A thin plate of sheet metal is located against the under side of the metal forming said raised housing portion and is welded thereto at 60 spots, indicated at 27^a and formed with re-

70 taining ears 28 for holding a flat spring 29 with which one end of the pivotally mounted locking bolt 30 engages. The plate 27 is also formed with portions 31 turned substantially at right angles at opposed sides, from 75 which narrower tangs 32 project, the latter being turned to engage against and hold the under plate 33 in place, this completing the lock. The pivotally mounted bolt to be moved by a key into and out of operative 75 position with the arm 12 is not new and a specific description of its construction and operation is not needed. The plate 27 at- 80 tached to a sheet metal latch housing is novel as well as the means used to retain 80 the two plates 27 and 33 together. This locking mechanism is simple and practical and is very effective in operation. It may be entirely dispensed with in those latches 85 where no lock is wanted.

90 This construction of latch mechanism is economically produced by stamping the parts from sheet metal, presents a good appearance and is fully practical, durable and efficient in all respects.

95 I claim:

1. In a latch, a sheet metal housing hav- 95 ing a raised portion one side of which is substantially flat, a plate of flat metal located within the raised portion and against 100 said flat side of the same, and provided with a part projecting through and above the top of the housing, and means consisting of electric welds between the plate and side of the 105 housing for permanently connecting them 110 together, substantially as described.

2. In a latch construction, a housing hav- 105 ing a raised portion provided with a slot in the top thereof, a member connected to the 110 housing and projecting outwardly from the top thereof, a handle comprised of two pieces of flat metal lying one at each side of the member and pivotally connected thereto and a third depending handle portion se- 115 cured to said pieces, one of said pieces hav- 110 ing an arm extending through the slot into the housing and the other having an arm passing alongside of the housing and turned laterally at its free end, and a spring dis- 120 posed between the first arm and the housing within the housing, substantially as de- 125 scribed.

3. A handle for latches formed from three pieces of flat metal, two of said pieces being disposed at the upper portion of the handle 120 in parallel spaced apart relation with their lower ends bent toward each other and con- 125 tacting with said other piece bent around the lower ends of the two upper pieces and se- 130 cured thereto, and an arm turned at an angle from the upper end of each of the first mentioned pieces, one of said arms having a lateral extension at its free end, substan- 135 tially as described.

4. In a latch construction, a housing hav- 130

ing a raised portion provided with a slot in the top thereof, a member connected to the housing and projecting outwardly from the top thereof, a handle having a divided upper end one part passing to each side of said member and pivotally connected thereto, each part being of flat relatively thin metal and one part passing into the housing through said slot, and the other part pass-

ing alongside of the housing and having 10 a section turned laterally at its free end, a sleeve around and secured to said section, and a spring in the housing acting against the part of the handle passed into the housing, substantially as described. 15

In testimony whereof I affix my signature.

DANIEL WEBSTER TOWER.
